CHARLES W. ANDREWS AND SELWYNE P. KINNEY, OF CHICAGO, ILLINOIS, ASSIGNORS TO H. A. BRASSERT & COMPANY, OF CHICAGO, ILLINOIS, A CORPORATION OF ILLINOIS

ROTARY DISINTEGRATOR

Application filed July 15, 1929. Serial No. 378,257.

This invention relates to a gas washing apparatus generally known as a disintegrator, and consists of the matters hereinafter described, and more particularly pointed out in the appended claims.

The disintegrator is of that type in which the gas and washing fluid are introduced into a casing containing alternately disposed, interacting, fixed and rotary disintegrator elements by means of which the gas and washing fluid are beaten together and the solid particles wetted by the washing fluid, are largely eliminated from the gas by centrifugal action of the disintegrator elements.

The object of our invention is an improved means of effecting a thorough wetting of the gas and positive mixture of the same with the water with the subsequent removal within the machine by the waste water of particles of wetted dust.

Another object of our invention is to improve the form and construction of the rotating and the stationary members, thereby improving the effectiveness of the cleaning action over methods which have hitherto been employed. The rotating or stationary members are ordinarily constructed of rounds, angles, T-bars or other shapes, fastened to the rotor, or respectively to the ring supporting the stationary members. In our invention we substitute for one or more of these rotating or stationary members a perforated member, preferably a cylindrical screen made from steel or other metal plate into which holes of suitable size and shape have been punched, drilled or cored. The surface of the screen may be corrugated in order to increase friction, although we do not recommend corrugations in cases where gases contain fumes which tend to stick to rough surfaces.

Other objects and advantages of the invention will be pointed out as we proceed with our specification.

In the drawings:

Figure 1 is a view representing a side elevation of the disintegrator with one wall thereof partially broken away to disclose the interior.

Figure 2 is a view representing a vertical section through the disintegrator in a plane indicated by the line 2—2 of Figure 1.

Figure 3 is a partial section in the same plane as that of Figure 2, showing a modified form of the device.

Referring now to that embodiment of the invention illustrated in the drawings:—10 indicates a casing comprising a voluted intermediate casing member 10a, with the volute disposed in a vertical plane; 10b, 10b indicate inlet casing members located at either side of and communicating with said intermediate casing member; and 11 indicates a horizontal shaft which carries the rotary disintegrator elements and the water distributing basket. Said shaft extends through the casing comprised of the members 10a and 10b and has its axis of rotation coincident with the axis of the voluted part of the intermediate member 10a. 12 indicates the discharge orifice of the voluted member 10a, said orifice being disposed with its axis of discharge tangential to the bottom part of the volute. 11c indicates the inlet passageways for the inlet members 10b. The casing as a whole is mounted upon a suitable base 13 and is preferably built of structural parts in such manner that it may be separated along the vertical median plane of the voluted shell member 10a and also on a horizontal plane through the central axis of the shaft 11, and may be thus conveniently disassembled to get at the parts within the casing for repairs or for removal and replace-

On the shaft 11 in the median plane of the voluted shell member 10a of the casing, is mounted a disk 14. Said disk is fixed between hub parts 15, 15 fixed upon the shaft 11 between a shoulder 16 and a threaded nut 16a thereon. The hub parts have annular flanges 17, upon which are fixed (as by a thread, as shown) cylindrical shells forming a basket 18 provided with annular, inwardly extending, radial end flanges 19. The shells forming the basket 18 are perforated and in said perforations are fixed radially projecting tubes or pipes 20. Said pipes are arranged in rows placed preferably at equal arcuate dis-

tances about the basket 18 (see Figure 1) and the number of pipes in a row and the number of rows of pipes may be varied in accordance with the width of the machine, its diameter and the speed of rotation of the shaft. Through these pipes, water, which as will later appear, is continuously collected in the rotating basket 18 and maintained about its periphery at a substantially constant depth therein, is discharged radially by centrifugal force towards the zone of disintegrating elements now to be described.

21 indicates a perforated cylindrical metal shell or screen surrounding the space occupied by the tubes or pipes 20, with its perforated wall concentrically disposed with reference to the shaft 11 and spaced but a short distance from the ends of the pipes 20. Said screen may be either fixed and carried by the side walls of the intermediate casing member 10a or may be rotary and be carried by the disk 14. As shown, and preferably, it is carried by the side walls of the intermediate casing member being made in two parts and secured thereto in any convenient manner, as by means of rings 25a. Beyond the perforated screen 21, there are fixed in the intermediate casing member 10a, to its side walls, horizontally disposed, inwardly extending disintegrator elements 22, 22. In alternation with said rows of fixed disintegrator elements are located radially spaced, horizontally disposed annular rows of disintegrator elements 23 carried by the disk 14 and extending to either side of said disk between the rows of fixed disintegrator elements.

The side walls of the casing member 10a have circular openings 24, 24 approximating in diameter the diameter of the perforated cylinder 21. These openings constitute inlets for the flow of gas from the inlet casing members 10b, 10b to the intermediate member 10a, and to and through the zone of the disintegrator elements, namely, the screen 21 and the elements 22 and 23. By the rotation of the disk 14, the familiar interaction and beating together of the washing water and gas is brought about by the rapid relative movement of the disintegrator elements.

The fixed disintegrator elements 22 have their ends extended into close relation with the disk 14, and the rotary disintegrator elements have their ends in like manner extended into close relation to the upright side walls of the casing member 10a. 25 indicates flat supporting rings at the ends of said bars. By this arrangement, the passageway otherwise presented for the gas, through the clearance spaces at the ends of the disintegrator elements, is blocked and the greater part of the gas is forced to pass through the zone of thorough effective disintegrator action.

Washing water is continuously introduced

into the casing by pipes 26 having fittings 27 fixed in and extending through the vertical side walls of the casing members 10b. Each of said fittings includes a part 28 with a discharge nozzle 29 which extends into the open end of the basket 18 in a direction tangential to the rotating shaft, being thus disposed to discharge water in the direction of the rotation of the basket, as shown in Figure 2.

The water discharged into the rotating basket 18 and maintained therein at a substantially constant depth about its periphery as heretofore stated, is ejected by centrifugal force from said basket through all the tubes or pipes 20, the outlet ends of which are quite near to the perforated screen 21. Said screen acts in effect, as the first disintegrator element, fixed or rotary, depending upon whether it is carried by the disk 14 or fixed to the casing, as shown herein. The pipes or tubes insure a positive distribution of the water in radially directed, closely spaced streams, with little or no diversion or dissipation until it reaches the screen element.

We have found by experimentation that better disintegration and mixing of the water and gas, and therefore a better wetting of dust particles, takes place in a ratio indirectly proportional to the size of the apertures in or between the rotating or stationary members. We therefore prefer to make the combined area of the apertures in the screen smaller than the open cross sections in the disintegrator through which the flow of the gas takes place. This has a further advantage of retaining both gas and water for a longer period within the machine, thus giving a more favorable time element.

The better cleaning effect with our type of construction over the ordinary disintegrator will be readily understood when it is conceived that water and gas are first thoroughly mixed in the circular space surrounding the water distributing basket where water and gas are thoroughly beaten by the rapidly moving tubes which completely fill the basket with a fine spray of water, then water and gas are forced to pass through numerous relatively small openings of a stationary or rotating screen; having passed this screen, water and gas meet with the moving disintegrator bars travelling at a still higher speed, this speed increasing with successive rows of rotary bars until the outermost members have been passed.

While we prefer to use only a single stationary screen facing the water distributing tubes, this screen may be made to revolve or several screens may be employed, but in any event the screen or screens should be followed by one or more sets of relatively rotating disintegrator bars, the surface blow of which is needed for the final removal of dust. The object of bringing the water into the basket

in this tangential manner is to facilitate its quickly finding a uniform level in the basket, due to centrifugal force. By locating the inlet pipes near the ends of the basket, more 5 water discharges through the outer than through the inner rows of pipes. In this manner the tendency of the incoming gas, flowing from the edge of the machine to the center and tending to sweep the water with 10 it, is effectively overcome as proved by careful experimentation. The relation of water admitted to the basket, to the out-flow from the basket through the tubes, is such that a certain spillage of water must take place at 15 the two outer edges of the basket. By this means a tangential spray is obtained which cuts across the two incoming gas streams at right angles to their flow and the gas entering the machine will divert this water through 20 the tubes and tend to keep the space between the tubes clean, the surface of the tubes thus being continuously wetted. In the case where gas containing heavy fumes or other gas difficult to clean is employed, we provide aper- 25 tures in the basket between the tubes, permitting additional water to flow from the gasket directly into the space between the tubes.

The bulk of the water passes from the 30 basket through the tubes and is forcibly thrown against the stationary screen which surrounds the outer open ends of the tubes at a short distance from the same. The screen causes an intimate mixture of water and gas 35 so that drops leaving tubes of say 1/8" in diameter become atomized to finer than 1/32", the fineness depending upon the speed of rotation of the basket. All the gas and all 40 the water are forced to pass together through these openings, thereby causing a thorough mixture with simultaneous compression, the most effective means of wetting the gas. There is no chance of the gas short circuiting the machine without being thoroughly 45 wetted.

Instead of making the disintegrator elements in the form of rods or bars 22, 23, as shown in Figure 2, said elements may be provided by means of perforated channel bars. 50 Such construction is shown in Figure 3. In this construction, 22a indicates the fixed disintegrator elements and 22b indicates the rotary disintegrator elements. In each case, the disintegrator consists of a channel bar bent into circular form and perforated to provide openings for the passage of the water and gas.

Having thus described our invention, what we desire to claim is:

60 1. In a disintegrator apparatus, in combination with a casing, a cylindrical basket rotatable in said casing, means for supplying water to said basket, a plurality of tubes adapted for discharge of water radially 65 from said basket, and a plurality of relative-

ly, rotative radially spaced disintegrator members operating in said casing radially beyond said basket, one of said disintegrator members being a fixed, cylindrical, perforated screen closely approached to the discharge 70 ends of the tubes carried by said basket.

2. In a disintegrator apparatus, in combination with a casing, a cylindrical basket rotatable in said casing, means for supplying water to said basket adapted to discharge 75 said water near the ends of said basket tangentially in the direction of its rotation, a plurality of relatively rotative, radially spaced disintegrator members operating in said casing radially beyond said basket, one of said 80 disintegrator members being a cylindrical, perforated screen closely approached to said basket.

3. In a disintegrator apparatus, in combination with a casing, a cylindrical basket 85 rotatable in said casing, means for supplying water to said basket at its ends in a direction tangential to its direction of rotation, a plurality of tubes adapted for a discharge of water radially from said basket, and a plurality 90 of relatively rotative, radially spaced disintegrator members operating in said casing radially beyond said basket, one of said disintegrator members being a fixed, cylindrical, perforated screen closely approached to the discharge ends of the tubes carried by 95 said basket, the total area of the perforations in said screen being less than any other open cross-sectional area in the machine.

4. In a disintegrator apparatus, in combination with a casing, a cylindrical basket rotatable in said casing, means for supplying water to said basket, a plurality of tubes adapted for discharge of water radially from 100 said basket, said basket being provided with a plurality of perforations intermediate said tubes, a plurality of relatively rotative, radially spaced disintegrator members operating in said casing radially beyond said basket, one of said disintegrator members being a 105 cylindrical perforated screen closely approached to the discharge ends of the tubes carried by said basket.

5. In a disintegrator apparatus, in combination with a casing, a cylindrical basket 115 rotatable in said casing, means for supplying water to said basket, a plurality of tubes adapted for discharge of water radially from said basket, a plurality of relatively rotative, radially spaced disintegrator members operating in said casing radially beyond said basket, one of said disintegrator members being a cylindrical perforated screen closely 120 approached to the discharge ends of the tubes carried by said basket and the remaining disintegrator elements being channel bars bent into cylindrical form concentric with the axis of rotation of said basket.

6. In a disintegrator apparatus, in combination with a casing, a cylindrical basket 130

- rotatable in said casing, said basket having
end flanges to determine the depth of water
carried thereby, means for supplying water
to said basket at its ends in a direction tan-
5. gential to its direction of rotation at a rate
to spill over said end flanges, a plurality of
tubes adapted for discharge of water radially
from said basket, and a plurality of relatively
rotative, radially spaced disintegrator mem-
10. bers operating in said casing radially beyond
said basket.

In testimony that we claim the foregoing
as our invention, we affix our signatures this
5th day of July, A. D. 1929.
